UNITED STATES PATENT OFFICE.

WALTER WAGNER, OF CHICAGO, ILLINOIS, ASSIGNOR, BY MESNE ASSIGNMENTS, TO
RAYVIO WATER COMPANY, A CORPORATION OF ILLINOIS.

LIQUID-DISPENSING DEVICE.

1,142,210.

Specification of Letters Patent.

Patented June 8, 1915.

Application filed February 29, 1912. Serial No. 680,622.

To all whom it may concern:

Be it known that I, WALTER WAGNER, a citizen of the United States, residing at Chicago, in the county of Cook and State of Illinois, have invented new and useful Improvements in Liquid-Dispensing Devices, of which the following is a full, clear, concise, and exact description, reference being had to the accompanying drawing, forming 5 a part of this specification.

My invention pertains to dispensing devices for drinking water, non-aerated beverages, and the like, and especially relates to water coolers of the kind in which a water-15 containing bottle is inverted upon an ice-cooled water-receiving vessel, from which vessel the water may be drawn from time to time, as desired, the water thus withdrawn from the vessel being replaced by water 20 from the bottle.

In the use of water coolers of the character set forth above, it is of course necessary to replace a bottle by a full one whenever it has become empty; and, in order that this 25 may be done, the full bottle must first be uncorked. It has been found that, in order to prevent the water from flowing out of the neck of the new bottle during the necessary tilting of the latter before placing it on the 30 cooler, the person whose duty it is to attend to the cooler will frequently place his hand over the mouth of the bottle, the palm of the hand being thus brought into direct contact with the drinking water. As the attendant 35 is usually a janitor, or some other person whose duties do not admit of great cleanliness of the hands, the possibility of handling the bottle in this manner is extremely undesirable from a sanitary standpoint. Even if the attendant should not 40 place his hand over the mouth of the bottle while inverting it, but should place the bottle in its inverted position in the cooler by a quick tilting movement, the result would be 45 that a considerable quantity of water would escape from the bottle during such movement, and the water receptacle would therefore become filled to a height above that of the mouth of the bottle, whereby any dirt 50 which might be present upon the outside of the neck of the bottle would be washed off into the drinking water; and this, also, is undesirable from a sanitary standpoint.

It is an object of my invention to provide 55 a liquid dispensing device which will not be

subject to the above disadvantages, which will be of a sanitary nature, and in which access of impurities to the water before it reaches the drinking glass is absolutely prevented.

A water cooler constructed in accordance with my invention, together with two forms of bottle closure, is described, by way of example, in the following specification, and shown in the accompanying drawing, in 60 which:

Figure 1 is a vertical section taken through the cooler, a bottle being shown in position therein; and Fig. 2 is a sectional view of a modified form of bottle closure.

Referring now to the drawing, 10 indicates an ice tank, within which is mounted a water-receiving vessel 11, the latter being provided with an outlet pipe 12 which passes through the ice tank and terminates, outside 65 the latter, in a faucet 13, by means of which water may be drawn from the vessel 11, as desired. The vessel 11 is open at its upper end, and is provided, at its top edge with a ring 14, of rubber or the like, upon which 70 the shoulder of the water bottle is adapted to rest when the bottle is in place in the cooler. By this means, a tight connection is made between the bottle and the top edge of 75 the vessel 11.

The parts, as described above, are of a well known construction, and consequently do not require detailed description here.

Located in the water vessel 11 is a stand 80 15 which, in the construction shown, comprises three legs 16, the ends of which rest upon the bottom of the vessel 11 and are sufficiently spaced apart so that they will engage the sides of the vessel and thus maintain the stand 15 at the center thereof. The 85 stand 15 is further provided with three upwardly extending arms 17, the ends of which are bent outwardly, so that the three arms form a guide for directing the mouth of the bottle toward the center of the stand 15. 90 The stand 15 is provided with an axial, upwardly projecting spike or pin 18, the function of which is to perforate the bottle closure when the bottle is inverted upon the vessel 11, and thus permit the water from 95 100 the vessel to flow into the vessel.

The bottle 19 is provided with a closure 105 which is adapted to be perforated by the spike 18. This closure consists of a disk 20, formed of lead foil or some other material 110

which may be torn with sufficient readiness, placed upon the mouth of the bottle, and secured in place by means of a threaded cap 21. The cap 21 engages screw threads 22 formed on the neck 23 of the bottle, and is adapted to be screwed firmly down upon the neck 23, so as to clamp the disk 20 securely in place. A gasket 24 is inserted between the disk 20 and the cap 21, so as to render the closure completely watertight. In order that the spike 18 may pass up into the neck 23 to perforate the disk 20, the cap 21 is formed with a central aperture 25.

In the practice of my invention, the bottles will be supplied ready provided with closures of the kind described above. When it is desired to place a full bottle in the dispensing device, no uncorking operation is required, it being merely necessary to invert the bottle and place it, mouth downward, in the vessel 11. The mouth of the bottle will thus be placed over the spike 18, which latter will enter through the aperture 25 of the cap 21, and will encounter and perforate the disk 20. When the disk 20 has thus been perforated, the water will flow from the bottle into the vessel 11, and, in flowing out, will still further tear the disk 20. The water will pour out of the bottle until the level of the water in the vessel has risen slightly above the plane of the mouth of the bottle. When the water in the vessel has reached this level, no more water can escape from the bottle, by reason of the fact that air cannot enter the bottle to displace the water. When, however, water is drawn off from the vessel 11 through the faucet 13, the level in the vessel will fall, and enough air will be admitted to the bottle to permit sufficient water to escape to restore the level of the water in the vessel 11. The level of the water in the vessel 11 thus remains constant, and never rises more than very slightly above the plane of the mouth of the bottle,—either when the bottle is first placed in the cooler, or thereafter. The guide arms 17 aid in bringing the mouth of the bottle into the correct position over the spike 18, and prevent the edge of the cap 21 from accidentally striking the spike.

It will be seen from the above that the water in the bottle is absolutely isolated until such time as the neck of the bottle has been placed fairly within the vessel 11. Provided, therefore, that the interior of the vessel 11 is clean—and there is no reason why it should not be clean, since it need never be touched—the water must necessarily run from the faucet 13 in precisely the same state of cleanliness in which it was originally bottled. It will, further, be noted that the water in the vessel 11 can never reach any dirt which may be present upon the neck 23 of the bottle, by reason

of the fact that the level of the water in the vessel never rises above the plane of the mouth of the bottle.

When it is desired to wash out the vessel 11, the stand 15 may be lifted out, thus leaving the interior of the vessel clear of any obstruction and enabling the stand 15 to be washed separately.

The closure employed is of simple construction, and may be cheaply made and placed in position; moreover, its use saves the time which is ordinarily spent in uncorking the bottle. When the bottles are refilled, it is a simple matter to insert a new disk 20 beneath the cap 21 in place of the old torn one.

In the modified form of closure shown in Fig. 2, the neck 23 of the bottle is formed with an upper groove 26 and a lower groove 27. The disk 20 is, in this modification, replaced by a metallic sheet 28, formed of lead foil or other material which may be torn with sufficient readiness. The edges of the sheet 28 are folded down around the neck 23; and the sheet is held in place by means of an elastic ring 29, formed of rubber or the like, which lies in the upper groove 26. A protecting cap 30, formed of paraffined paper or the like, is placed over the sheet 28, and is secured in place by means of a metallic clamping ring 31. In the use of this form of closure, the protecting cap 30 is removed previously to the placing of the bottle in the cooler. When the cap 30 has been removed, the bottle may be inverted and placed, mouth downward, in the vessel 11, whereupon the spike 18 will perforate the sheet 28, just as was the case with the disk 20.

While I have described and shown one embodiment of my invention, and a modified form of closure, I wish it understood that changes may be made in the constructions shown, and that the invention is susceptible of being embodied in other forms.

What I claim being:

1. In a device for dispensing drinking water and non-aerated beverages, the combination with a bottle-supporting, liquid-receiving vessel having means for permitting the liquid to be drawn therefrom as desired and having its upper end open for the reception of the neck of an inverted bottle, of a liquid-containing bottle adapted to be inverted into the open upper end of said vessel and have its neck project down into the vessel, a fragile puncturable seal affixed to said bottle for closing the opening thereof, which seal maintains the opening closed even after the bottle has been inverted, and a seal-puncturing device mounted within said vessel adapted to puncture said seal as the bottle is lowered into position and project through the seal into the mouth of the bottle when the bottle is in

its lowered position, said seal and puncturing device being so constructed that after the seal has been punctured a water-flow opening will be formed in the seal between 5 the walls of the punctured portion and the side of the puncturing device to permit the water to flow freely from the bottle into the vessel, the seal being affixed to and removable with the bottle when the bottle is removed from the vessel after having been emptied.

2. In a device for dispensing drinking water and non-aerated beverages, the combination with a bottle-supporting, liquid-receiving vessel having means for permitting the liquid to be drawn therefrom as desired and having its upper end open for the reception 15 of the neck of an inverted bottle, of a liquid-containing bottle adapted to be inverted into the upper end of said vessel and having its neck project down into the vessel, a fragile puncturable seal affixed to said bottle for closing the opening thereof, which seal maintains the opening closed even after the 20 bottle has been inverted, and a seal-puncturing device removably mounted within said vessel adapted to puncture said seal as the bottle is lowered into position and project through the seal into the mouth of the bottle when the bottle is in its lowered position, said seal and puncturing device being so constructed that after the seal has been punctured a water-flow opening will be formed in the seal between the walls of the 25 punctured portion and the sides of the puncturing device to permit the water to flow freely from the bottle into the vessel, the seal being affixed to and removable with the bottle when the bottle is removed from the vessel after having been emptied.

3. In a device for dispensing drinking water and non-aerated beverages, the combination with a bottle-supporting, liquid-receiving vessel having means for permitting the liquid to be drawn therefrom as desired and having its upper end open for the reception 45 of the neck of an inverted bottle, of a liquid-containing bottle adapted to be inverted into the open end of said vessel and have its neck project down into the vessel, a seal having a fragile puncturable portion affixed to said bottle for closing the opening thereof, which seal maintains the opening closed even after the bottle has been inverted, and a seal-puncturing device mounted within said vessel adapted to puncture said seal as the bottle is lowered into position and project through the seal into the mouth of the bottle when the bottle is in its lowered position, said seal and puncturing device being so constructed that after the seal has been punctured a water-flow opening will be formed in the seal between the walls of the 50 punctured portion and the side of the puncturing device to permit the water to flow

freely from the bottle into the vessel, the seal being affixed to and removable with the bottle when the bottle is removed from the vessel after having been emptied.

4. In a device for dispensing drinking water and non-aerated beverages, the combination with a bottle-supporting, liquid-receiving vessel having means for permitting the liquid to be drawn therefrom as desired and having its upper end open for the reception 70 of the neck of an inverted bottle, of a liquid-containing bottle adapted to be inverted into the open upper end of said vessel and have its neck project down into the vessel, a fragile puncturable seal affixed to said bottle for closing the opening thereof, which seal maintains the opening closed even after the bottle has been inverted, a seal-puncturing device mounted within said vessel adapted to puncture said seal as the bottle is lowered into position and project through the seal into the mouth of the bottle when the bottle is in its lowered position, means for guiding the mouth of a bottle toward said puncturing device, said seal and puncturing 75 device being so constructed that after the seal has been punctured a water-flow opening will be formed in the seal between the walls of the punctured portion and the side of the puncturing device to permit the water to flow freely from the bottle into the vessel, the seal being affixed to and removable with the bottle when the bottle is removed from the vessel after having been emptied.

5. In a device for dispensing water or 80 non-aerated beverages, the combination with a liquid-receiving vessel having means for permitting liquid to be drawn therefrom as desired, and having its upper end open for the reception of the neck of an inverted bottle, and a stand removably mounted in said vessel, said stand being provided with an upwardly projecting spike, and having upwardly extending arms for guiding the neck of the bottle toward said spike, of a liquid-containing bottle adapted to be inverted into the open upper end of said vessel, and a seal affixed to said bottle, said seal having a perforable portion adapted to be encountered and perforated by said spike, 85 when said bottle is inverted into said vessel.

6. In a device for dispensing drinking water and non-aerated beverages, the combination with a bottle-supporting, liquid-receiving vessel having means for permitting the liquid to be drawn therefrom as desired and having its upper end open for the reception 100 of the neck of an inverted bottle, of a liquid-containing bottle adapted to be inverted into the open end of said vessel and have its neck 105 project down into the vessel, a closure seal for said bottle comprising a sheet of fragile perforable material across the opening of said bottle for closing said opening, which seal maintains the opening closed even after 110

the bottle has been inverted, and a seal-puncturing device mounted within said vessel adapted to puncture said seal as the bottle is lowered into position and project
5 through the seal into the mouth of the bottle when the bottle is in its lowered position, said seal and puncturing device being so constructed that after the seal has been punctured a water-flow opening will be formed
10 in the seal between the walls of the punctured portion and the side of the puncturing device to permit the water to flow freely

from the bottle into the vessel, the seal being affixed to and removable with the bottle when the bottle is removed from the 15 vessel after having been emptied.

In witness whereof, I have hereunto subscribed my name in the presence of two witnesses.

WALTER WAGNER.
